UNITED STATES PATENT OFFICE.

CHARLES V. HETTS, OF DETROIT, MICHIGAN.

SASH-CENTER.

1,299,183.

Specification of Letters Patent.

Patented Apr. 1, 1919.

Application filed January 13, 1919. Serial No. 270,831.

To all whom it may concern:

Be it known that I, CHARLES V. HETTS, a citizen of the United States, residing at Detroit, county of Wayne, State of Michigan, have invented a certain new and useful Improvement in Sash-Centers, and declare the following to be a full, clear, and exact description of the same, such as will enable others skilled in the art to which it pertains to make and use the same, reference being had to the accompanying drawings, which form a part of this specification.

My invention relates to sash centers and it consists in certain improvements herein-after described and claimed.

In the drawings:

Figure 1 is a perspective view of the sash center in place upon the sash and the jamb with the construction partly outlined in dotted lines.

Fig. 2 and Fig. 3 represent the two halves of the sash center.

Fig. 4 represents the block therein which carries the friction rollers.

Fig. 5 and Fig. 6 represent the fastenings of the back of the sash center and are details of Fig. 7.

Fig. 7 is a cross section on the line Y—Y of Fig. 8.

Fig. 8 is a plan view of the jamb side of the sash and a reverse view of Fig. 3.

Fig. 9 is a view of one of the rollers.

Fig. 10 is a cross section on the line X—X of Fig. 7.

Similar letters refer to similar parts.

In the drawings A represents one of the sections of the center which is mortised into and attached to the jamb. B is the other plate and section which is mortised into and attached to the sash. Obviously, however, these could be reversed in case it is desired to do so. C is a block which has a center or swivel part at C'. The rear side of this block is shown in Fig. 8. The face side, that is the side outwardly toward the block B when assembled, is shown in Fig. 3 at C². The longitudinal section of this block C is shown in Fig. 7 on the line Y—Y of Fig. 8 and a cross section of it is shown in Fig. 10 which is on the line X—X of Fig.

7. The block B has radial grooves B' B² B³ B⁴. These grooves are repeated until the whole block is divided into sections and

grooves as shown in Fig. 2. The block C is peculiarly shaped and fits into a mortise 55 or recess in the block A, the mortise or recess being lettered C³ C³ Fig. 3, in which the face of the block appears. The central portion of the block is hollow as shown at C' Fig. 7 and is raised from the surface forming a cup shaped part which encircles a spiral spring S. A holding bolt D is inserted inside of the spiral spring and pressed through a recess E (see Figs. 2 and 7) in the block B. A head D' is preferably 60 formed on the end of the bolt D and a washer D² as shown in Fig. 6, is passed underneath the head D', and the tension of the spring holds the parts together. On the block C and in the cavities C² C² when it is 65 passed into or through the block A are inserted friction rollers F like that shown in Fig. 9. The block C being elastically held in position for the spring S holds the rollers in place with frictional tension against the 70 block B and as the sash centers are turned one upon the other, the roller passes over the elevations in the block B and falls into the 75 grooves B² B³ etc., according to the amount of turning. The tension of the spring holds 80 the parts in any position in which it may be placed until the application of force places the sash centers in a different position.

The block C is narrower than the diameter of the roller and the mortise or orifice C³ in 85 block A, as shown in Fig. 10, is enlarged toward the junction of the two blocks, the friction roller is larger than the mortise or orifice C³, as shown in cross section in Fig. 10. The elasticity of the spring S allows 90 the block C to oscillate to some extent as the friction rollers pass over the ridges between the concavities B¹ B², etc., and therefore avoid the necessity of a perfectly accurate construction as well as avoiding binding 95 as would probably be the case if there was no variation allowed.

To assemble this the block C must be placed in the block A from the rear side toward the jamb, the rollers inserted from 100 the face side as they will not go through the mortise or cavity C³. The block B is then placed over the rollers with any one of the grooves B¹ B² etc., the block connecting with the friction rollers. The 105 spring S is then placed in the pocket C',

the bolt D is placed through the whole and compressed until the washer D² can be arranged around its neck at D¹.

Its operation may be fully understood from the foregoing description.

What I desire to claim is:

In a sash center the combination of a block adapted to be fixed in position to the jamb, a secondary block adapted to be fixed 10 in position to the sash, one of said blocks having a longitudinal perforation a third block adapted to be held in position by a

spiral spring and a bolt, said spring and bolt, said third block projecting into the perforations in one of said first mentioned 15 blocks, friction rollers impinging against said third block of a diameter larger than the perforations in said block, means for holding said bolt and spring and the three blocks in position when assembled, substantially as described.

In testimony whereof, I sign this specification.

CHARLES V. HETTS.
